US00D719974S

(12) **United States Design Patent**
Knutson et al.

(10) **Patent No.:** **US D719,974 S**
(45) **Date of Patent:** **** Dec. 23, 2014**

(54) **DISPLAY SCREEN OR PORTION THEREOF
WITH GRAPHICAL USER INTERFACE**

(71) Applicant: **Dropbox, Inc.**, San Francisco, CA (US)

(72) Inventors: **Morgan Knutson**, San Francisco, CA (US); **Ryan Putnam**, Colorado Springs, CO (US)

(73) Assignee: **Dropbox, Inc.**, San Francisco, CA (US)

(**) Term: **14 Years**

(21) Appl. No.: **29/453,290**

(22) Filed: **Apr. 26, 2013**

(51) **LOC (10) Cl.** **14-04**

(52) **U.S. Cl.**

USPC **D14/490**

(58) **Field of Classification Search**

CPC G06F 3/048; G06F 3/0481; G06F 3/04817

USPC D14/485-495

(57) **CLAIM**

The ornamental design for a display screen or a portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with graphical user interface showing our new design; and, FIG. 2 is a front view of a second embodiment thereof.

The broken lines around the Figures show a display screen or portion thereof that form no part of the claimed design.

1 Claim, 2 Drawing Sheets
(1 of 2 Drawing Sheet(s) Filed in Color)
